The ornamental design for a soap holder with grips for holding a bar of soap, as shown and described.

DESCRIPTION

FIG. 1 is a top plan view of the soap holder with grips for holding a bar of soap showing my new design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is an enlarged top perspective view thereof.

FIG. 1

FIG. 2

FIG. 3

FIG. 4

FIG. 5

FIG. 6

FIG. 7
